UNITED STATES PATENT OFFICE.

FRANK H. TREGO, OF BUFFALO, NEW YORK.

DESIGN FOR A VEHICLE-AXLE.

42,406.

Specification for Design.

Patented Apr. 9, 1912.

Application filed January 27, 1912. Serial No. 673,949. Term of patent 7 years.

To all whom it may concern:

Be it known that I, FRANK H. TREGO, a citizen of the United States, residing at Buffalo, in the county of Erie and State of New York, have invented a new, original, and ornamental Design for Vehicle-Axes, of which the following is a specification, reference being had to the accompanying drawings, forming part thereof.

Figure 1 is a top plan view of a vehicle

axle showing my new design. Fig. 2 is a side view thereof. Fig. 3 is a bottom plan view of the same.

I claim:

The ornamental design for a vehicle axle, as shown.

FRANK H. TREGO.
